UNITED STATES PATENT OFFICE.

CLARENCE E. WAKEFIELD, JOSEPH P. FLEMING, AND JOSEPH F. OLIVER, OF WORCESTER, MASSACHUSETTS, ASSIGNEES TO WAKEFIELD ALL-STEEL WRENCH COMPANY, INC., OF WORCESTER, MASSACHUSETTS, A CORPORATION OF MASSACHUSETTS.

SOCKET-WRENCH SET.

Application filed April 1, 1927. Serial No. 180,255.

The present invention relates to socket wrench sets, comprising a plurality of sockets of graduated sizes and a common handle or shank, which is provided for use, selectively, with any one of said socketed members.

Our invention resides in the compact assemblage of such a set in a specially constructed holder or container, the latter being of simple and inexpensive construction, and adapted to prevent accidental displacement of the parts of the set while permitting them to be removed, when desired, with the utmost ease.

Further objects of the invention will be apparent from the following detailed description, taken in connection with the accompanying drawings, in which—

Fig. 1 is a top plan view of the improved holder with the wrench parts assembled therein.

Fig. 2 is a view in side elevation of the assembly.

Fig. 3 is an end view of the device, as seen from the left in Figs. 1 and 2.

Fig. 4 is a transverse sectional view on the line 4—4 of Fig. 1.

Fig. 5 is a fragmentary sectional view, showing a ratcheting device capable of use with the socket members of the set.

Like reference characters refer to like parts in the different figures.

A socket wrench set of the type referred to provides, as is well known, a plurality of similarly shaped socket members 1, 2, 3, 4, 5, 6, 7 and 8, graduated in size, and each having a nut or bolt-receiving socket, here shown as hexagonal in form, and adapted to fit a given size of nut or bolt, ranging from a large nut or bolt, for which the member 1 is provided, to a small nut or bolt, for which the member 8 is provided,—intermediate sizes being taken care of by the socket members 2 to 7 inclusive. These socket members are graduated not only as to diameter, but also as to depth, and each provides, in addition to its socketed nut-engaging portion, a polygonal opening 9, all of the openings 9 being of the same size and shape, so as to be capable of operative engagement with the similarly shaped handle or shank member 10, common to all of said socket members.

As here shown, the openings 9 are hexagonal and the handle member 10 is of hexagonal section to fit all of said openings 9. Preferably, as shown in Fig. 1, one end of the shank or handle 10 is bent at right angles, as indicated at 11; either end of the handle can be inserted in any of the socket members, depending upon whether the long portion or the short portion of the handle is to be used as a lever arm. The present wrench set includes, in addition to the usual handle 10, a ratcheting device or handle 12 of ordinary construction, adapted for use selectively with any one of the socket members 1 to 8 inclusive of the set. As shown in Fig. 5, the member 12 provides a ratchet 13, which is operatively engaged by a pawl 14, said ratchet 13 having a hexagonal opening therethrough for the entrance of a similarly shaped extension member 15, whose end, like the ends of handle 10, is adapted to be operatively engaged with any one of the socket members 1 to 8 inclusive. The extension member 15 provides at its opposite end a screw driver blade 16, so that the set also affords, when desired, a ratcheting screw driver.

According to the invention, we provide a shallow tray or holder 17, preferably made from a single elongated piece of sheet metal, whose longitudinal edges are bent up to provide parallel side walls 18, 18', and whose ends are bent up to provide one end wall 19, substantially the same height as the side walls 18, 18', and another end wall 20 of greater height. Along the edge of end wall 19, the material of the tray has an extension which is curled over to form an eyelet or hinge 21, for a purpose to be hereinafter described.

The tray 17 receives, longitudinally, the bent handle member 10 laid flatwise therein, as shown in Fig. 1, with its edge against the side wall 18. Also said tray receives, transversely, the extension member 15, laid flatwise on the bottom of said tray, preferably between the bent end 11 of handle 10 and the end wall 19. Against the inner long edge of handle 10 is packed the ratcheting device 12, the latter seating edgewise of the bottom of the tray, as shown in Fig. 1. The remaining area of the bottom of said tray accommodates the socket members 1 to 8 inclusive, when laid in a row with their sides against said bottom and their ends against

that wall 18' which is farthest removed from the handle 10. In so disposing the socket members 1 to 8 inclusive, the largest member 1 is placed adjacent the high end 5 of wall 20 of the tray, with the sizes of the other socket members gradually decreasing toward the other end of the tray, so that the smallest member 8 is adjacent the short portion 11 of handle 10.

10 In order to hold each socket member 1 to 8 inclusive against sidewise displacement on the bottom of tray 17, the material of said bottom is struck up to provide a plurality of transverse upright tongues 22, 22, 15 each of a height sufficient to project above a horizontal plane through the center or axis of the adjacent socket member. Thus each socket member is engaged snugly on its side by a stop or tongue adapted to prevent side- 20 wise rolling along the bottom of the tray; and a similar tongue 23 is preferably struck up from the bottom to provide a clip for holding the ratchet extension member 15 against the end wall 19 of the tray. In 25 order to prevent endwise shifting of the several socket members 1 to 8 inclusive, away from side wall 18' of the tray, additional longitudinal tongues 24, 24 are struck up from the material of the bottom, these tongues 24, 24 each being preferably of sufficient length to span a pair of adjacent socket members, so as to retain them against end- 30 wise movement. As shown in Fig. 1, the ratcheting member 12 bears against the 35 tongues 24 on the opposite sides of said tongues from the socket members 1 to 8 inclusive, and in order to prevent shifting of said ratcheting member 12 from this position, it is desirable, though not necessary, to 40 strike up additional tongues 25 and 26 for engagement with the opposite surface of said ratcheting member 12, the last named tongue 26 also engaging the handle member 10, to 45 clip it firmly against the side wall 18 of the tray. Another struck-up tongue 27, Fig. 1, may be provided to bear against the end of extension member 15, and thus it will be seen that all of the various parts of the set are held 50 firmly against shifting movement on the bottom of the tray by tongues or clips that engage said parts and define the respective spaces reserved on the tray bottom for their reception. Another tongue 28, Fig. 1, underlies the end of handle member 10, there- 55 by to elevate said end from the tray bottom with the handle held in an inclined position, for a purpose to be hereinafter described.

60 A resilient wire 29 is inserted through the eyelet or hinge portion 21 of end wall 19, and is bent substantially at right angles beyond each end of said hinged portion, so that one section 30 of said wire will overlie the socket members 1 to 8 inclusive, while the other section 31 of said wire will overlie 65 the handle member 10; both sections over-

lie the extension member 15 and the bent end 11 of handle 10. The section 30 runs the full length of the tray 17, and at its free end is adapted to be entered in a laterally ex- 70 tending notch 32 of end wall 20, thereby to latch said wire in retaining relation to all of the socket members, while at the same time pressing the section 31 of said wire into contact with handle 10. Said section 31 has its lengthwise termination substantially at the 75 point where, due to the elevation of handle 10 by lug or tongue 28, the upper surface of said handle is substantially flush with the upper surface or edge of ratcheting device 12,—and at this point said section 31 is 80 formed with a transverse bend 33, Fig. 1, so that a downward retaining pressure is exerted both on said handle 10 and on said ratcheting device 12.

In the position of parts shown, the hinged 85 wire 29, by its sections 30, 31 and 33, serves as an all-inclusive retaining device for the parts of the socket wrench set, when the free end of section 30 is latched into the notch 32. To release the wrench set parts 90 from the holding-down pressure of the sections 30, 32 and 33, said free end of section 30 is sprung out of the notch 32, and thrust upwardly, this serving to rock the entire wire 29 about the pivot provided by the eyelet or hinge 21, into a substantially upright position, thereby allowing the removal of any or 95 all of the parts contained in the tray 17.

We claim:

1. A tray or container for the sidewise reception on its bottom of a row of interchangeable socket members of different lengths of a socket wrench set, with portions of the material of said bottom struck up from the plane thereof at different distances 100 from one side wall of said tray, each such portion being of sufficient length to span a pair of adjacent socket members, thereby to confine said pair of socket members against said side wall.

2. A tray or container for the sidewise reception on its bottom of a row of interchangeable socket members of a socket wrench set, and also for the edgewise reception on its bottom of a common handle and common ratcheting device for said members, a wire hinged to one end wall of said tray, and providing two sections overlying the tray bottom, one section for substantial contact 105 with all of said socket members, and the other section for contact with said handle member and ratcheting device, and means projecting from the bottom of said tray to elevate said handle member, thereby to make its upper surface flush with the edge of said ratcheting device.

Dated March 30, 1927.
